PRESSURE FLUID FOLLOW-UP
SERVOMOTOR

William F. Triplett, Grand Junction, Colo.

Application April 16, 1945, Serial No. 588,861

12 Claims. (Cl. 121—39)

1

This invention relates to a power-operated reversing device for locomotives, and has for its principal object the provision of a safe, easily operated and positive mechanism for replacing the usual hand-operated reverse lever.

Another object of the invention is to construct the device so that it can be operated by either air or steam pressure at the will of the engineer, and to provide means which will automatically connect the reversing mechanism with a manual mechanism should both the steam and air pressure fail so that operation thereof will be under the control of the engineer at all times and under all conditions.

Still another object is to provide a power-operated mechanism which will not "creep," and which will accurately maintain its setting until a change is desired.

A further object is to provide a device of this character which can be connected with any of the standard valve motion at present used upon locomotives without change therein and with a minimum of installation expense.

A still further object is to provide an easily operated manual adjustment which may be used in the locomotive shop for accurately pre-setting the valves.

A still further object is to provide automatic means for completely disengaging the power mechanism when the hand mechanism is in use, and for locking the air supply valve during manual operation so that air or steam pressure cannot be accidentally turned on when the hand mechanism is in use; and to so construct the hand mechanism that it may be completely disconnected and turned out of the way of the engineer during power operation of the devices.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a diagrammatic view illustrating the relative positions of the various elements of the improved power-operated reversing device on a typical locomotive;

Fig. 2 is a side view of the power mechanism of this device;

Fig. 3 is a plan view thereof;

Fig. 4 is an enlarged, fragmentary side view, partially in section, illustrating a rack and pinion employed in the device;

Fig. 5 is a cross-section, taken on the line 5—5, Figs. 3, 4 and 6;

Fig. 6 is a longitudinal section, taken on the line 6—6, Figs. 3 and 5.

Fig. 7 is a detail side view of the control-mechanism for the improved reversing gear in the power operating position as it would appear from the inside of the locomotive cab;

Fig. 8 is a detail section through the control mechanism, taken on the line 8—8, Fig. 9;

Fig. 9 is a vertical section, taken on the line 15 9—9, Fig. 8, as it would appear with the controls in the manual operating position;

Fig. 10 is a detail section, taken on the line 10—10, Fig. 9; and

Fig. 11 is a similar section, taken on the line 11—11, Fig. 9, illustrating in solid line the "manual" position of the elements and in broken line the "power" position thereof.

In Fig. 1, typical parts of a locomotive are indicated diagrammatically and designated by numeral as follows: driving wheels 12, cab 13, boiler 14, steam dome 15, air receiver 16, reversing gear fork shaft 17, linkage-supporting lever 18, and reversing fork lever 19.

The improved power reversing mechanism is operated from a pressure motor 20, preferably, but not necessarily of the reciprocating type, to which steam may be conducted from the steam dome 15 through a steam supply pipe 21, controlled by a steam valve 22 and a non-return check valve 23, or air may be conducted from the air receiver 16 by means of an air supply pipe 24, controlled by a second non-return check valve 25. The supply of fluid, either steam or air, is controlled by a valve 26 in the cab 13, which will be later described, and flows from the latter valve to the motor 20 through a motor supply pipe 26.

The motor 20 may be of any desired type. As illustrated, it is a V-type motor having a built-in reversing shaft 27 connected to a conventional reversing valve which, when turned in one direction, causes the motor to operate forwardly and, when turned in the other direction, causes the motor to operate rearwardly. A reversing lever 28 is mounted on the reversing shaft 27 of the motor for the purposes of this invention.

The motor rotates a motor gear 29, which is indicated in broken line in Fig. 6, through which power is supplied to the improved reversing device. A shifting gear 30, slidably mounted on a

Worm shaft 31, can be shifted into mesh with the motor gear 28. The worm shaft 31 rotates a worm 32, which in turn rotates a worm gear 33. The worm gear 33 is mounted on a pinion shaft 34 carrying a suitable pinion 35. The pinion 35 meshes with the teeth of a toothed rack bar 36 to reciprocate the latter forwardly and rearwardly.

The forward extremity of the rack bar terminates in a crosshead rod 38, which in turn terminates in a crosshead 37 slidably mounted in a crosshead guide 38. The crosshead guide 38 is bolted to the forward extremity of a rack housing 40 which is mounted on a gear case 41 in which the worm 32 and the worm gear 33 are contained. The gear case 41 provides a mounting base for the motor 28. The entire structure is supported at the side of the locomotive on suitable brackets 37.

A connecting link 39 connects the crosshead 37 to the reversing fork lever 19. Thus, it can be readily seen that, when the motor 28 is operated forwardly, it will swing the fork lever 19 forwardly, and when operated rearwardly, it will similarly swing the fork lever 19 rearwardly. The latter lever, of course, operates as usual to adjust the reversing linkage of the locomotive.

The reversing lever 28 is controlled from a control lever 42 at the engineer's position. The lever 42 is pivoted on a lever shaft 43 intermediate its extremities and a reach rod 44 extends from the lower extremity of the control lever 42 forwardly to a floating lever 45. The upper extremity of the floating lever 45 is suspended from the lower extremity of the reversing lever 28, the reach rod 44 being connected below the point of suspension. A return rod 46 extends from the lower extremity of the floating lever 45 to a bracket plate 47 secured to the crosshead 37.

The operation of the linkage and levers is as follows: Let us assume that the engineer's control lever 42 is pulled rearwardly. This will push the reach rod 44 forwardly so as to swing the upper extremity of the floating lever 45 forwardly, the lower extremity thereof acting as a fulcrum. This swings the reversing lever 28 forwardly and causes the motor 28 to operate in a reverse direction, so as to rotate the pinion 35 to actuate the rack bar 36 rearwardly and move the fork lever 19 to a "reverse" position. As the crosshead 37 moves rearwardly, it in turn pushes the lower extremity of the floating lever 45 rearwardly to cause it to pry against the reach rod 44 as a fulcrum so that the upper extremity of the lever 45 will return the reversing lever 28 to the closed position, thus stopping the motor 28. The point of stoppage depends upon the amount of the original movement of the engineer's control lever 42.

Forward movement of the control lever 42 causes an opposite operation to take place; that is, it first swings the reversing lever 28 rearwardly. This causes the motor to operate forwardly to push the crosshead 37 forwardly, and the latter in turn acts back through the return rod 46 and the floating lever 45 to return the reversing lever 28 to its closed or neutral position when the crosshead has moved the pre-set distance.

Thus, the engineer can set the crosshead 37 at any desired point, depending upon the pre-setting of the control lever 42. The setting of the latter is maintained by means of a toothed locking segment 48 into which a toothed latch 49 engages when a hand grip 50 on the lever 42 is

released. The grip 50 is connected with the latch 49 through the medium of a grip link 51.

The supply of fluid under pressure to the motor supply pipe 26 is controlled by the hand grip 50. A push rod 72 extends from a lever arm 73 on the grip 50 into a receiving socket 74 on a cam cap 75. The cam cap rides in a cam groove 76 in a cylindrical cam member 77 mounted on the lever shaft 43. Thus, when the cam cap 75 is rotated in one direction, it will move inwardly on the cam member 77, and when rotated in the other direction, it will move outwardly thereon. A compression spring 78 constantly urges the cam outwardly.

A plunger 79 extends from the cap 75 through the lever shaft 43 in alignment with a valve stem 80 on the valve 85. Thus, when the hand grip 50 is compressed, it causes the push rod 72 to rotate the cap 75, causing the latter to actuate the valve stem 80 to open the valve 85. A valve pipe 86 connects the valve 85 with the stem and air lines 21 and 24. The motor supply pipe 26 is also connected into the valve 85, so that whenever the hand grip 50 is compressed, fluid under pressure will be admitted to the motor 28.

In order that a power-operated reverse gear be practical, it is necessary that means be provided for operating the device should the air pressure fail. In the present device, should the air in the air receiver 16 have insufficient pressure to operate the motor 28, the engineer can turn on the steam valve 22. The steam will force the check valve 25 closed to prevent steam from entering the receiver 16, and the device can then be operated on steam pressure. However, at times it is necessary, more particularly when the engine is in the shop, to operate the reverse gear for setting the valves, etc., when there is neither air nor steam pressure. This condition is accommodated in the present invention by providing a manual operating mechanism.

Since it would be practically impossible to operate a manual mechanism with the motor 28 connected to the device, means are provided for disconnecting the motor when manual operation is desired. This is accomplished by placing a pressure cylinder 52 in alignment with the worm shaft 31 and placing a piston 53 on the shaft 31 within the cylinder 52. The piston 53 is rotatably mounted on one extremity of a spool 54, the other extremity of which carries the shifting gear 30. The spool is splined on the worm shaft 31 so that it may move longitudinally thereof but cannot rotate thereon. The spool 54, however, can rotate in the piston 53.

A compression spring 55 constantly urges the spool 54 toward the cylinder 52 so as to move the shifting gear 30 out of mesh with the motor gear 28. The spool 54 is moved in the other direction, so as to engage the gears 29 and 30, by fluid pressure in the cylinder 52. The fluid flows through a cylinder pipe 56 from the motor supply pipe 26.

Thus, whenever pressure is supplied to the motor 28, this pressure will be simultaneously supplied to the cylinder 52 to force the shifting gear 30 into mesh with the motor gear 28 and, whenever there is no pressure on the motor, these gears will be forced out of mesh by the spring 55 and the worm shaft 31 can be rotated manually. When the piston 53 is in its fully extended position, it contacts a shoulder 57, which holds it stationary so that the spool 54 may rotate therein to prevent wear on the piston and rings.

Manual rotation is accomplished through the

medium of a hand crank 57 at the engineer's position. The hand crank 57 is mounted on a crank shaft 68 which is journalled in a rotatable bearing member 58 mounted on a cam shaft 59 supported from the locking segment 48. When not in use, the crank 57 is swung forwardly to the solid line position of Fig. 7, and when desired for use is pulled rearwardly to the horizontal broken line position in this figure. This forward and rearward swinging movement of the crank rotates the cam shaft 59.

The shaft of the crank 57 is connected through a universal joint 60 from which a splined or square stub shaft 69 extends. The stub shaft 69 is slidable within a socket sleeve 70 which is sufficiently long. The sleeve 70 is mounted on the extremity of a universal shaft 71, which connects through a universal joint 72 with a clutching member 62 journalled in alignment with the extremity of the worm shaft 31. The clutching member 62 terminates in a clutch head 63 which can be moved into engagement with clutch dogs 64 on the extremity of the worm shaft 31.

Thus, as the crank 57 is swung from its inoperative (solid line) to its operative (broken line) position, the stub shaft 69 will slide forwardly into the socket sleeve 70 until the universal joint 60 contacts the end of the sleeve 70, as shown in broken line in Fig. 7. It will then act to push the universal shaft forwardly to cause the clutch head 63 to engage the dogs 64, thus connecting the crank 57 to the worm shaft 31 so that the latter may be rotated manually by means of the crank 57 to operate the fork lever 19.

Means are provided to prevent pressure from reaching the motor 20 when the crank 57 is in the manual operating position. This is accomplished by placing a cam 81 on the cam shaft 59 so as to be rotated by rotation of the bearing member 58. The cam 81 is positioned below an arcuate lifting member 82 which is mounted for vertical movement in the locking segment 48. The lifting member 82 is positioned below a contact roller 83 mounted on the lower extremity of a fulcrum rod 84 extending upwardly along the control lever 42 and terminating against a spring 85 therein.

The lever arm 73 of the hand grip 50 is pivoted at 86 on the fulcrum rod 84. The purpose of the fulcrum rod is to make it impossible for the valve 65 to be opened when the manual control is in operation, for when the crank 57 is swung to the operative position, the cam 81 will lift the lifting member 82. This in turn will contact the roller 83 and lift the fulcrum rod 84. This raises the latch 49 out of the teeth of the segment 48 and also raises the push rod 72 in its socket 74 so that operation of the hand grip can no longer cause the push rod to operate the cam cap 18. Thus, during manual operation the lever 42 is free to move with the movements of the crosshead, and all pressure is shut off from the motor 20 and the cylinder 52.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A power-operated reversing device comprising: a toothed rack; a pinion in mesh with said rack for reciprocating the latter; a pressure-operated motor; means connecting said motor to said pinion so that operation of the former in

either direction will move said rack in either direction; a reversing valve controlling the direction of operation of said motor; a reversing lever operating said valve; a control lever; means connecting said control lever with said reversing lever for swinging the latter to an open position; means operable from said rack for returning said reversing lever to the closed position after the rack has moved a predetermined distance; a fluid conduit for supplying fluid under pressure to said motor; a feed valve controlling said conduit; a hand grip on said control lever; and means connecting said hand grip to said feed valve so that operation of said grip will open said feed valve.

15 2. A power-operated reversing device comprising: a toothed rack; a pinion in mesh with said rack; a pinion shaft carrying said pinion; a worm wheel on said pinion shaft; a worm in mesh with said wheel for rotating the latter; a worm shaft carrying said worm; a pressure-operated motor; a drive gear operable from said motor; a shifting gear slidably splined on said worm shaft; a spool member extending along said worm shaft from a connection with said shifting gear; a piston carried by said spool; a pressure cylinder around said piston; means for admitting fluid under pressure to said pressure cylinder from the motor supply to cause the piston to force the shifting gear into mesh with the motor-operated gear when fluid is turned to said motor, one extremity of said pinion shaft extending entirely through said spool; clutching means engaging said latter extremity; and manual means for engaging and rotating said clutching means when desired.

35 3. A power-operated reversing device comprising: a toothed rack; a pinion in mesh with said rack; a pinion shaft carrying said pinion; a worm wheel on said pinion shaft; a worm in mesh with said wheel for rotating the latter; a worm shaft carrying said worm; pressure-operated motor; a drive gear operable from said motor; a shifting gear slidably splined on said worm shaft; a spool member extending along said worm shaft from a connection with said shifting gear; a piston carried by said spool; a pressure cylinder around said piston; a feed valve for admitting fluid under pressure to said pressure cylinder from the motor supply to cause the piston to force the shifting gear into mesh with the motor-operated gear when pressure is turned to said motor; spring means for urging said shifting gear out of mesh with said motor gear when the fluid is shut off from said motor; and manual means for rotating said worm shaft; means for clutching said manual means to said worm shaft when desired; and means for preventing operation of said feed valve when said means for clutching is in operation.

40 4. A combined manual and power-operated reversing gear for locomotive comprising: a reversing device; a pressure motor; pressure-operated means for connecting said pressure motor to said reversing device; a manual crank; a bearing member for said crank arranged to be rotated in a plane parallel to the axis of said crank; and means for automatically connecting said crank to said reversing device when said bearing member is rotated to a predetermined position.

45 5. A combined manual and power-operated reversing gear for locomotives comprising: a reversing device; a pressure motor; pressure-operated means for connecting said pressure motor to said reversing device; a control lever; a reversing valve controlling said motor; means connecting said control lever with said valve to con-

trol the direction of operation of said motor; a feed valve controlling the fluid pressure to said motor; a hand grip on said control lever; and means for operating said feed valve from said hand grip.

6. A combined manual and power-operated reversing gear for locomotives comprising: a reversing device; a pressure motor; pressure-operated means for connecting said pressure motor to said reversing device; a manual crank; a bearing member for said crank arranged to be rotated in a plane parallel to the axis of said crank; means for automatically connecting said crank to said reversing device when said bearing member is rotated to a predetermined position; a control lever; means connecting said control lever with said pressure motor to control the direction of the latter; a valve controlling the fluid pressure to said motor; a hand grip on said control lever; means for operating said valve from said hand grip; and means operable by the rotation of said bearing member for disconnecting said hand grip from said valve when said bearing member has been rotated to said position.

7. A control lever for a combined power and manually-operated reversing gear comprising: a pressure-operated motor operatively connected to said gear; a reversing valve controlling the operation of said motor; a lever; a connecting member between said lever and said reversing valve for controlling the latter; a hand grip on said lever; and a feed valve operable from said hand grip for controlling the fluid pressure to said reversing valve.

8. A control lever for a combined power and manually-operated reversing gear comprising: a lever; a connecting member between said lever and said gear for controlling the latter; a hand grip on said lever; a valve operable from said hand grip for controlling the fluid pressure to said gear; a locking segment; a latch member operable from said hand grip for locking said lever in said locking segment; a hand crank; means connecting the hand crank with said reversing mechanism to operate the latter manually; a rotatable bearing for said hand crank so that the latter may be swung out of the operative position; and means operable from the rotation of said bearing for rendering said hand grip inoperative with reference to said valve and said locking segment.

9. Means for operating a reversing device, either manually or by means of a fluid motor, as desired, comprising: a reversing valve on said motor; a control lever operatively connected to said reversing valve; a hand grip on said control lever; a feed valve for said motor; means connecting the hand grip and feed valve to open said feed valve upon movement of said hand grip; clutching means between said motor and said reversing device; and means to operate said clutching means responsive to pressure fluid controlled by the opening of said feed valve.

10. Means for operating a reversing device, either manually or by means of a fluid motor, as desired, comprising: a reversing valve on said motor; a control lever operatively connected to said reversing valve; a hand grip on said control lever; a feed valve for said motor; means connecting the hand grip and feed valve to open said feed valve upon movement of said hand grip;

clutching means between said motor and said reversing device; means to operate said clutching means responsive to pressure fluid controlled by the opening of said feed valve; a swingingly mounted manual crank; a second clutching means; and means operable from the swinging movement of said crank for engaging said second clutching means so that said device can be operated manually from said crank.

10 11. Means for operating a reversing device, either manually or by means of a fluid motor, as desired, comprising: a reversing valve on said motor; a control lever operatively connected to said reversing valve; a hand grip on said control lever; a feed valve for said motor; means connecting the hand grip and feed valve to open said feed valve upon movement of said hand grip; clutching means between said motor and said reversing device; means to operate said clutching means responsive to pressure fluid controlled by the opening of said feed valve; a swingingly mounted manual crank; a second clutching means; means operable from the swinging movement of said crank for engaging said second clutching means so that said device can be operated manually from said crank; locking means for locking said control lever at any desired point; and means operable from the swinging movement of said crank for unlocking said locking means so that said control lever will be free during manual operation.

15 12. Means for operating a reversing device, either manually or by means of a fluid motor, as desired, comprising: a reversing valve on said motor; a control lever operatively connected to said reversing valve; a hand grip on said control lever; a feed valve for said motor; means connecting the hand grip and feed valve to open said feed valve upon movement of said hand grip; clutching means between said motor and said reversing device; means to operate said clutching means responsive to pressure fluid controlled by the opening of said feed valve; a swingingly mounted manual crank; a second clutching means; means operable from the swinging movement of said crank for engaging said second clutching means so that said device can be operated manually from said crank; and means for automatically disconnecting said hand grip from operative connection with said feed valve when said crank is swung to the manual operating position.

WILLIAM F. TRIPLETT.
